ARTHUR H. GAEBEL, OF LARCHMONT, NEW YORK, ASSIGNOR TO THE GAEBEL CORPORATION, OF NEW YORK, N. Y.

ALL-METAL TELESCOPIC BOX FOR CAMERAS.

Application filed May 14, 1926. Serial No. 109,128.

This invention belongs to the class of substantially rectangular and will be detachable cameras, and has particular reference to the chamber or box construction which embodies the object lens and plate holder for carrying out focusing operations.

The principal object of the present invention is to provide a camera, particularly a copying camera, with a chamber or box which will be durable, easily operated for carrying out focusing operations, and which will be capable of withstanding considerable strains and stresses.

Another object of the invention is to produce a means of the indicated character which will be made of metal and of novel construction to permit of telescopic action, and yet effectively exclude all light except that admitted through the object lens.

The nature of the invention and its distinguishing features and advantages will appear when the following specification is read in connection with the accompanying drawing, in which—

Figure 1 is a sectional elevation of the chamber or box embodying the present invention; the showing being merely representative of one embodiment.

Fig. 2 is a sectional plan view.

Fig. 3 is a detail of a modified form of construction.

The present invention contemplates the provision of a chamber or box for comparatively heavy copying cameras with which focusing operations may be readily carried out. To this end there is provided a suitable number of box-like sections which are telescopically associated or related, and means for supporting and adjusting the sections with respect to each other, and means for maintaining the proper alignment of the sections and for guiding and for causing the sections to move equally at each side of their major or longitudinal axes. In the present instance three box-like sections 10, 11 and 12 are provided to constitute a chamber or box with which will be associated the object lens, shown at 13 carried by the section 12, and a plate or film holder 14 associated with or carried by the section 10. The section 10 is of double wall construction, there being a wall 15 and a wall 16 which are held in spaced relationship by a wall 17 attached to the walls 15 and 16 by virtue of flanges 18 on the walls 15 and 16 respectively. The wall 17 is sub-

stantially rectangular and will be detachable. Each of the walls 15 and 16 is also provided with an inturned portion or flange 19 for a purpose to appear. The section 11 is of double wall construction, there being a wall 20 and a wall 21 which are held in spaced relation by a wall or plate 23 which is attached to flanges 24 respectively on the walls 20 and 21. The wall or plate 23 is detachable, suitable fastening elements being used for this purpose. Each of the walls 20 and 21 is provided with an inturned flange 25 for a purpose to appear. The section 12 is of single wall construction and is provided with side walls 26 and a removable end wall 27. The end wall 27 carries the lens 13, and the side walls 26 embody flanges 28. The section 11 is capable of telescopic association with the section 10, and the section 12 is capable of telescopic association with the section 11. In the present instance the section 12 is fixedly supported on brackets 29 which are secured to a base or support 30. The section 10 is guided for movement on tracks 31 carried by the base 30 by virtue of rollers 32 on the under side of the section 10 and which are associated respectively with the tracks 31.

In order to effect the telescopic movement of the sections 10 and 11 with respect to each other, and both with respect to the section 12 there is provided small pinions 33 fixed to an axle 34 arranged transversely at the under side of the section 10 near the rear thereof, the said axle being supported in bearings 35 attached to the bottom wall of the section 10. The teeth of each of the pinions 33 meshes with teeth on a rack 36 attached to the base 30. A hand wheel 37 is employed, the same being fixed to one end of the axle 34. It follows therefore that by turning the hand wheel 37 movement of the section 10 will be caused through the coaction of the pinions 33 with the racks 36. In this way focusing operations are carried out; the section 11 moving into the section 10, whereas the section 12 moves into the section 11. The flanges 24, 25, and 28 constitute a means for limiting the telescopic movement of the several box-like sections.

In order to maintain the several sections in alignment, and for aiding in guiding the sections in their movements, and for causing the sections to move equally at each side of their major or longitudinal axes, there

are provided pinions 38, carried respectively by the sections 10 and 12, and racks 39 carried by the walls 20 and 21 respectively of the section 11. The pinions 38 are arranged in pairs fixed to an axle 40 which is mounted in bearings 41. In the telescopic action, the racks 39 move either with respect to the pinions 38 or are stationary while the pinions themselves rotate.

10 It is to be noted that by making the walls or plates 17, 23 and end wall 27 removable, it is possible to disassociate the several box-like sections.

15 In Fig. 3 there is shown a modification in which in lieu of the rectangular walls or plates 17 and 23, each of which is disposed substantially at a right angle with respect to the walls with which they are connected, there is provided a wall 45 which is arranged at an angle so as to deflect any light which may possibly get into the spaces between the walls of the sections.

20 It is to be understood that the box-like sections may be of any size and proportion and are made of metal to give the desired strength and rigidity and to provide the proper degree of durability.

25 It is to be understood that the invention is not restricted to the precise arrangement of parts shown and described, as details of construction may be modified and rearranged without departing from the spirit of the invention, the scope of which is limited only by the terms of the appended 30 claims.

I claim:

1. A camera chamber or box comprising box-like sections telescopically associated means to which one of said sections is fixedly secured, means supporting the other sections for telescopic adjustment with respect to the fixed section, and means for effecting the telescopic adjustment of the adjustable sections.

40 2. A camera chamber or box comprising box-like sections telescopically associated, means to which one of said sections is fixedly secured, means supporting the other sections for telescopic adjustment with respect to the fixed sections, means for effecting the telescopic adjustment of the adjustable sec-

tions, and means limiting the telescopic adjustment of said adjustable sections.

3. A camera chamber or box comprising box-like sections telescopically associated, means to which one of said sections is fixedly secured, means supporting the other sections for telescopic adjustment with respect to the fixed section, means for effecting the telescopic adjustment of the adjustable sections, means maintaining the alignment of the adjustable sections, and means causing the adjustable sections to move equally at each side of their major or longitudinal axes.

4. A camera chamber or box comprising metallic box-like sections telescopically associated, means to which one of said sections is fixedly secured, means supporting the other sections for telescopic adjustment with respect to the fixed section, and means for effecting the telescopic adjustment of the adjustable sections.

5. In a copying camera, a chamber or box comprising box-like sections telescopically associated, one of said sections of single wall construction, each of the other sections of double side wall construction, and means for effecting the telescopic adjustment of certain of said sections.

6. In a copying camera, a chamber or box comprising metallic box-like sections telescopically associated, one of said sections being fixed, the other sections telescopically adjustable with respect to each other and with respect to the fixed section, and means for effecting the telescopic adjustment of the adjustable sections.

7. In a copying camera, a chamber or box comprising metallic box-like sections telescopically associated, one of said sections being fixed, the other sections telescopically adjustable with respect to each other and with respect to the fixed section, means for effecting the telescopic adjustment of the adjustable sections, the fixed section being of single wall construction, and each of the adjustable sections being of double side wall construction to provide light wells between the sections respectively.

ARTHUR H. GAEBEL.
